UNITED STATES PATENT OFFICE.

WILLIAM E. SMALL, OF BROOKLYN, NEW YORK.

HEEL-BUILDING DEVICE.

Application filed February 1, 1921. Serial No. 441,538.

To all whom it may concern:

Be it known that I, WILLIAM E. SMALL, a citizen of the United States of America, residing at 452 Green Avenue, Brooklyn, in 5 the county of Kings and State of New York, have invented certain new and useful Improvements in Heel-Building Devices, of which the following is a specification.

This invention relates to a device for 10 shaping and building heels for shoes, wherein lifts of various sizes and shapes are selected, glued and assembled together, then the whole assembled heel pressed, when they are then ready for further operation.

15 An object of my invention is to provide a simple, cheap and expeditious way of building up heels of various sizes and shapes is a suitable building member or device, which is not only substantial and reliable but is also permanent, so that the same device may be continuously used for the purpose, and when the heel is further completed may be fitted to the shoe with no difficulty and with accuracy. With such 20 device the operator is enabled to build heels of a given height with the utmost facility, without having to employ a great variety of special or adjustable forms, or the attending to the other numerous detail required by such devices or machines.

Another object of my invention is to provide a device upon which either flat or inclined heels may be built, the device having a breast plate which may be calibrated for 25 the purpose of producing any number of different varieties of height of the heel by the one device without any alteration or changes wherein heels of any desired height, pitch and size may be built, after which the heel 30 so built, is placed under pressure, by which means each and every heel built is pressed to a given height.

With the foregoing and other objects in view, further objects and advantages will 45 appear as the description of the invention is hereinafter developed.

Referring to the drawings wherein is shown what is now considered to be the preferred form of my invention:

50 Figure 1, is a side view of my heel building device applied to a machine.

Figure 2, an enlarged, partial top plan view of the breast plate showing key and heel in position.

55 Figure 3, a partial top plan view of parts

shown in Figure 1, showing one slide extended ready to receive the lifts.

Figure 4, a partial section view of the clamping device.

Figure 5, a built up heel detached from 60 the device.

Figure 6, a modified form of breast plate.

Figure 7, shows another modified form of that shown in Figures 2 and 6.

There are two forms of built up heels, 65 one in which the various lifts are nailed together, and the other where they are glued or cemented together; it is to this latter class to which my invention is an improvement.

70 It is the style at present to have high heels on all of the ladies' shoes and slippers, and it is with great difficulty they are built, and by reason of the methods employed, cause the production of perfect heels at a 75 great expense, first on account of the necessity to have a great number of various forms both special and adjustable for the building of the several special styles, and secondly on account of the imperfect ones so 80 made with such special and adjustable devices.

85 My device is applicable to be applied to any of the well known machines or may be used separate therefrom, or used by a device wherein there will be a base, 1, suitably supported by a column, 2, adapted to revolve around the same, either manually or by power. Above such base is provided a pressure board, 3, which is adjustable thereon—by means of a nut, 4; and which causes uniform pressure on the heels as they are so introduced under such pressure board, the shoulder, 5, being such as to not only sustain the parts, but also such pressure as 90 may be exerted in pressing the various lifts of the heel together.

95 Referring to the Figure 1, the base 6 of the heel building device comprises a number of sliding members, 7, each having secured 100 to its front end a breast plate 8, the latter may have a bore, 9, in which is a suitable guide 10, having an extension therefrom preferably in the shape of a dove tail 11 which forms a key, to which each and every 105 lift 34 is applied, and which, together with the breast plate 8 prevents any movement of the lifts to the right or left or backwards by reason of the key holding them secure. At 12 may be pivoted an equalizer 13 adapt- 110

ed to be raised or lowered by any suitable means, such, for instance, as a movable wedge 14 that may be suitably held in line with the equalizer by a bolt 15 after making the adjustment for the proper height heel.

When the operator is about to build heels, he extends the slide 7 as shown in Figure 3; he sitting in front of the device with the necessary sizes of lifts 34 grouped about him so as to be convenient to reach and apply to the form. After the various lifts have had adhesive material applied and have been assembled in the device one on the other, the slide 7 is then pushed back as shown on Figure 1, where it is locked to the extension 16, such extension may have a lever 17 provided with a slot, which when fitted over the pin 18 on the breast plate 8, will clamp the parts together and prevent separation when further pressure is applied to the heel.

The extension 16 is provided with a sleeve 37 carrying on the upper end a gear 38, said sleeve and gear are threaded internally to receive a screw 19, carrying on its upper end a roller 21 and on the lower end provided with a pivoted foot 22, which will adapt itself to any angle that the heel may be built. To the rear of the screw may be placed a suitable support 23 for a pressure arm 24, the latter adapted to be brought down on the top of the gear 38 in any approved manner, but in this particular instance it is preferred to use an eccentrically pivoted lever 25, having a handle 26, which by turning the same causes the pivoted foot to be forced against the top of the built up heel. This is what may be termed the first pressure.

The base 1 containing the slide 7 and carrying the extension 16, may be turned around manually or by power as is usual on machines, with the result that another slide is presented to the operator, thus the same operations are repeated over and over again, each heel as it receives the requisite number of lifts to have it of a given height, has a certain amount of pressure applied immediately to squeeze all superfluous glue or cement from between the layers or lifts, and while the next heel is being built the said cement in the previous built heel has become set so that a further pressure may be exerted on the built up stack of lifts 34 by an auxiliary clamping means, such for example as by turning by hand or otherwise the small pinion 27, suitably mounted on the extension 16, and which meshes with the gear 38. As each heel is finished, it in turn is introduced to the various pressure till they reach the presser table, where the heel receives its final and constant pressure, till finally released from the device, when it will be found that each and every lift is absolutely and perfectly locked to the others,

so that it is only necessary to be further shaped for the shoe.

About 30 to 50 heels are made before the heel first made, passes completely around under the pressure board 3, after it has thus passed around, the operator may extract the dove tail key, to release the heel, which when removed from the form will be as represented in Figure 5, being sufficiently dried to stand any further operation as may be applied to it for any or all other purposes.

Again in addition to the dove tail key it may be found advantageous under certain circumstances to place non-slip projections or spurs 29 on the breast plate as shown in Fig. 6. The non-slips may be permanently fixed on the breast plate 8, there being no necessity for them to be otherwise, as the heel will readily become detached from the device as soon as the key 11 is extracted therefrom. Again, these non-slips may fit within like apertures in each of the lifts, by this means there is no possible way in which any of the lifts may slip or slide to one or the other side, even if the lifts are a little thicker on one side than the other. Again, where a low flat heel may be employed as for example on men's shoes, slippers, etc., where no wedge lifts are necessary, it will be found advantageous to provide only the non-slips 29, as they would hold the several layers of lifts that would be assembled, any one or more of which may be of an uneven thickness from moving sidewise when the pressure is applied. The non-slips will not only provide against slipping sidewise, but will act as the key to hold the lifts in position when the pressure is placed upon the mass.

As a further convenience and means for expediting the work, a foot treadle 30 is suitably pivoted at 31 to the standard 2, and may be provided with any suitable means for returning the same, as for example by a spring 32, and having a foot rest 33 for the operator to extract the key 11.

By my device it will be seen that it is absolutely impossible for the lifts when assembled on the dove tail key 11 with their faces against the breast plate, to slip or slide sidewise or otherwise, by reason of their faces being locked in contact with the breast plate. Thus with my device as has been before noted any size, height or shaped heel may be formed on the device without any changes, the one device answering for any and all purposes of heel building.

With my device it is proposed to use glue or cement, and it is my purpose to apply the same with the brush as is also usually done at the present time, but it may be applied by spraying each of the lifts in any suitable manner before they are placed one on the other, again, the leather may be glued or otherwise treated with an adhesive, be-

fore the various size pieces are cut out, in which case it would only be necessary to spray water over the various lifts to sufficiently moisten the glue to make them adhere to the others when placed in position. Thus it will also be seen the various size lifts to build a given size, shape and height heel may be so assembled in the shortest possible time, with the maximum amount 10 of certainty as to their height and perfection and after the said heels have passed around under the pressure board 3, every heel will be perfect in every detail. Again as will be noted, all forms whether they 15 be "special" or "adjustable" are dispensed with, thus causing a great saving.

It is usual in the old methods to build a number of dozens of pairs of heels before any are placed under pressure. They 20 are built and allowed to stand till the required number to fill a board have been made, then they are placed thereon, and the lot placed under pressure.

Again by building heels in such manner, 25 the lifts slip and slide according to the pressure to one side or the other, or under certain circumstances they may slip backwards, this is always possible when building heels with wedge shaped lifts, in these stock 30 forms referred to, and pressing them as described. Thus it is, that each and every defective heel must be torn apart and cleaned before reassembling, in which case it is extra expense. In my improvement 35 herein described and shown all of such defects are not only cured but cannot occur.

In accordance with the provisions of the Patent Statutes, I have herein described the principle of my invention which I now consider to represent the best embodiment 40 thereof, but I desire to have it understood that the various forms are only illustrative and that the invention can be carried out in other ways than those described.

Also while I have described the means 45 for extracting the key, yet it is to be understood that the key could remain stationary in the device shown in Fig. 2 and the built up heel removed instead. Again it is to be understood that instead of the locking key protruding from the breast plate and having a way in the lifts, that these conditions may be reversed as shown in Fig. 7, by numerals 11', 29' and 34' with all the 50 efficiency and exactness of that previously described, it being merely a matter only from the manufacturer's point of view.

While the pressure board as shown is cut away for some distance so as to permit of 55 the various pressure regulating devices being applied to the built up heel, yet it will be understood that such board which is stationary may be provided with an inclined or beveled approach, where the roller when 60 it reaches the same is gradually forced fur-

ther downward by reason of the work table being revolved, until the roller has reached the end of the incline, where the same uniform pressure will be applied to the several assembled heels while thereunder. These 70 and all other changes are intended to come within the scope of the claims.

Having thus described my invention, what I claim as new and desire to secure by Letters Patent is:

1. The method of building heels of separate lifts which comprise assembling said lifts one upon another, interlocking said lifts with a holder for preventing slipping of the lifts with respect to each other, applying pressure to the assembled mass, and unlocking said mass after pressure has been applied.

2. The method of building heels of separate lifts which comprises assembling said lifts one upon another, applying an adhesive to the lifts, interlocking said lifts to a holder for preventing slipping of the lifts with respect to each other, applying pressure to the assembled mass, and unlocking 80 said mass after pressure has been applied.

3. A heel building device comprising in combination, a breast plate, a platform, pivotally mounted adjacent thereto, for receiving the lifts, means for varying the inclination of said platform, means for applying pressure to the lifts, and means for locking 90 said lifts to said breast plate.

4. A heel building device comprising in combination, a breast plate, a platform secured thereto for receiving the lifts, a plunger movable towards said platform for applying pressure to the lifts, and a plurality of means for selectively forcing said plunger against the lifts.

5. A heel building device comprising in combination, means for receiving the lifts, a rotatable sleeve, a plunger threaded within said sleeve, a support within which said sleeve is slidably mounted, means for sliding said sleeve together with said plunger for applying pressure to the lifts, and means for rotating said sleeve.

6. A heel building device comprising in combination, a rotatable member provided with lift receiving means, a rotatable sleeve slidably mounted with respect to said member, a plunger threaded within said sleeve, means for sliding said sleeve together with said plunger for applying pressure to the lifts, means for rotating said sleeve, and means including a stationary table for applying further pressure to said plunger.

7. A heel building device comprising a plate against which the lifts are adapted to abut, and a guide co-operating with said plate and provided with a locking extension for holding the lifts in place.

8. A heel building device comprising a plate against which the lifts are adapted 130

1
to abut, and means for locking the lifts to said plate.

9. A heel building device comprising a plate against which the lifts are adapted 5 to abut, said plate being provided with means for co-operating with the lifts to lock the latter in assembled position.

10. A heel building device comprising a plate against which the lifts are adapted 10 to abut said plate being shaped to fit the breast of the lifts, and means for locking the lifts to said plate.

11. A heel building device comprising a breast plate, a guide co-operating therewith 15 and provided with a locking extension, a platform pivotally mounted adjacent said breast plate for receiving the layers of lifts, and means for varying the inclination of said platform.

20 12. A heel building device comprising a sliding base having a heel building breast plate a movable guide centrally located within the same and having an outwardly extending locking means secured thereto, non- 25 slips located on each side of such last mentioned means for holding the lifts in position, a movable means suitably secured to the breast plate whereby flat or inclined heels may be assembled to the desired 30 height, and means for extracting the locking means from the mass after pressure has been applied.

13. A slideable heel building device secured to a revolving platform provided 35 with means for holding lifts of various sizes in place against movement in either of a plurality of directions, in combination with a movable foot adapted to be applied to the top of the assembled layers, and means for 40 applying a plurality of pressures to the assembled mass before being removed from said device.

14. The combination in a device for building heels of lifts, of a breast plate, of lifts 45 provided with means for locking them to such breast plate, of means for applying pressure to the stack of lifts, and means permitting the removing of the built up mass from the device.

50 15. The combination of a pillar or support for heel building machines provided with a working revolving table, such table provided with a plurality of movable heel building devices, means therein for holding 55 securely the several layers of lifts, means for locking the pressure means to the device, with means for applying pressure to the assembled mass, of additional screw pressure applying means, and auxiliary

means for so applying it, and a pressure 60 board for operating on the roller carried by said screw to give a uniform pressure to all the various forms thereunder, whereby the heels will all be of a uniform height.

16. In a heel building device, having a 65 pillar or support for the revolving work table, the combination of a presser board adjustably mounted on said support, a plurality of heel building devices carried by the work table, an extension on each 70 device adapted to be locked thereto and having pressure exerting means thereon to be applied to the assembled lifts, and additional means for applying pressure to said lifts. 75

17. A heel building device having a base with a breast plate, movable means for securely holding the lifts against slipping or sliding, a cover for such device provided with a means for locking it to the base 80 and having an opening, a sleeve fitting within said opening provided with a gear, a suitable threaded rod adapted to be operated through said sleeve, said rod having a pivoted foot on its lower end, and a roller 85 on its upper end, a pressure lever adapted to press on the sleeve, and on the assembled mass, a second gear to mesh with the gear on the sleeve whereby further pressure is applied to the foot, and a pressure table 90 so arranged that when the roller enters thereunder the entire mass of lifts is given a uniform pressure.

18. A heel building device provided with 95 a key for holding the various lifts in relative position to each other.

19. A heel building device having an equalizer hinged therein with means for adjusting it thereto, a movable key for holding the lifts on the equalizer, and means 100 for extracting the key after pressure has been applied.

20. That method of building up heels for boots and shoes from separate lifts, which consists in providing each lift with an interlocking portion, stacking the lifts in superposed relation on a guide having a complementary interlocking portion, and slidably interlocking said portions of the lifts and the guide, compressing the superposed lifts into a homogeneous heel structure, and finally removing the interlocking portion of the guide from the compressed heel structure to free the same. 110

In testimony whereof I have affixed my 115 signature.

WILLIAM E. SMALL.
